UNITED STATES PATENT OFFICE

157,713

SHOE CLEANING ATTACHMENT

Henry Thomas, Los Angeles, Calif.

Application July 2, 1949, Serial No. 3,683

Term of patent 7 years

(Cl. D9—2)

To all whom it may concern:

Be it known that I, Henry Thomas, a citizen of the United States, residing at Los Angeles, in the county of Los Angeles and State of California, have invented a new, original, and ornamental Design for a Shoe Cleaning Attachment, of which the following is a specification, reference being had to the accompanying drawing, forming part thereof.

I claim:

The ornamental design for a shoe cleaning attachment, as shown and described.

HENRY THOMAS.
